UNITED STATES PATENT OFFICE.

HARRY A. ADAMS, OF DANVILLE, ILLINOIS, ASSIGNOR TO ALLITH-PROUTY COMPANY, OF DANVILLE, ILLINOIS, A CORPORATION OF ILLINOIS.

DOOR-OPENING MECHANISM.

Application filed June 2, 1917. Serial No. 172,362.

To all whom it may concern:

Be it known that I, HARRY A. ADAMS, a citizen of the United States, residing in the city of Danville, county of Vermilion, and 5 State of Illinois, have invented certain new and useful Improvements in Door-Opening Mechanism, of which the following is a specification.

My invention refers to sliding doors and 10 particularly to hinged, folding doors and has special reference to a novel means for opening and closing such doors.

Folding doors are coming more generally into use than heretofore, they being preferred 15 for use in dividing a large, spacious room into several small rooms. Also, they are adaptable to garage, stable, warehouse and similar uses.

Since the advent of automobiles various 20 and sundry means have been devised for providing closures for garages. Where there is space to permit garages have been built having sufficient room in which to accommodate swinging or sliding doors but 25 where there is not sufficient space to permit of the installation of swinging or sliding doors other closure means have been devised. These means comprise generally two or more doors of comparatively narrow width hinged 30 together to form what is known as folding or accordion doors and which fold back against the side of the building to which they may be attached. To carry the doors across the door opening these have been provided 35 with hangers which run in or on suitable track secured to the upper portion of the doorway. Where there is a single doorway that is one wide enough only for a single vehicle a folding door comprising only two

40 sections may be used. On the other hand when it is desired to close a large opening sets of doors may be used each set of doors fastened to the sides of the doorway and provided with proper track hanger equipment. Doors of this character sometimes 45 are very heavy and it is difficult to move them into opened or closed position. Furthermore, it is desirable to adapt means to 50 the doors so that they may be opened or closed from a distance. It is also desirable to provide means to lock the doors when closed and have such locking means operable by the opening and closing mechanism.

The devices which have been employed for

opening and closing doors of the character 55 contemplated by my invention have not been positive in their action. The locking means have not been of such a nature as to positively lock the doors when in closed position, and means have not been provided to 60 fully move the doors into closed position, thus making a tight fitting doorway.

To overcome these and the other objections I have devised a door opening mechanism, one object of which is to provide 65 means for opening and closing folding doors by mechanical means.

Another object is to provide means whereby the door may be locked and unlocked by the operating mechanism. Another object 70 is to provide means in the operating train which will positively prevent damage to the power element or to the doors if the doors should ever be stopped by some obstacle during the opening or closing movement.

A still further object is to provide means in connection with the opening and closing mechanism to positively move the doors into tightly closed position. A still further object is to provide means whereby the doors 75 may be gently brought to a fully closed or fully opened position without any shock or jar.

A still further object is to provide yielding means in the operating train to compensate for obstacles which may be in the line of movement of the doors and to permit operation of the motor when the doors are stopped by said obstacles. A yet further object is to provide means for stopping the doors 80 when striking obstructions without 90 damaging the motor and doors.

A yet further object is the provision of means interposed in the connections between 95 the prime mover and the door, whereby the movement of the doors may be completed when interrupted at any point in the travel thereof by reason of encountering an obstruction, or whenever the prime mover becomes ineffective to complete such movement.

These and other objects will be apparent to those skilled in the art from a study of the drawings, wherein—

Fig. 1 is an elevation of the upper portion of half a doorway showing the preferred form of my mechanism.

Fig. 2 is a similar view showing the other

half of the upper portion of the doorway. Fig. 3 is a plan view of Fig. 1 with the motor removed.

Fig. 4 is an enlarged view of the mechanism which operates the locking bar.

Fig. 5 is an end elevation of Fig. 4.

Fig. 6 is a plan view taken on line 6—6 of Fig. 1.

Fig. 7 is an enlarged plan view of the clutch mechanism at the power end of the shaft and the closing device, the doorway being shown in section.

Fig. 8 is an elevation showing more in detail the yielding connection between the shaft and the doors.

Fig. 9 is an enlarged sectional view on line 9—9 of Fig. 8.

Fig. 10 is a plan view showing the position of the several elements when the doors are in partially opened position.

Fig. 11 is an enlarged horizontal sectional view through the yielding means when in the position of Fig. 10, and

Fig. 12 is a diagrammatic representation of the preferred form of wiring connections with the motor.

Fig. 13 is a diagrammatic representation of a means for preventing the circuit coils E and F from being closed at the same time.

In the drawings 10 indicates the upper portion of a double doorway having the usual side members 11 and 12. Hinged to the side post 11 are doors 13 and 14, the doors being hinged together on the rear side of the joint 15. In similar manner doors 16 and 17 are joined to post 12 at the doorway, these also being hinged together at the joint 15. Extending along the upper portion of the doorway are track members 18 and 19 which may be set at an angle to the doorway as shown in Figs. 3 and 7. The reason the track members 18 and 19 are set preferably at an angle is to permit the closing of the doors against the side or end wall of the building, the controlling feature being the positioning of the outer end of the track with respect to the doorway 10. If it is desired to fold the doors back against the wall flush with the doorway, then the outer end of the pieces of track would be positioned nearer the doorway than indicated in Figs. 3 and 7.

Extending along the doorway 10 carried in suitable bearings 24 is a shaft 25 having at one end a bevel 26 and the other end provided with a clutch 27 carrying at its outer end bevel 28 which meshes with a large bevel 29 mounted on a vertical shaft 30. In like manner a similar bevel 26 meshes with the bevel 31 mounted on a vertical shaft 32. Shafts 30 and 32 cooperate with pivots in check members 33 and 34 which are preferably similar to swinging door checks which checks are fastened to the pivots and are adapted to turn with the shafts 30 and 32.

The check members 33 and 34 are of the plunger type which is commonly used in double acting swinging doors, the purpose being to afford a shock absorbing means so that when power is applied to open the doors, the doors may be opened slowly, also brought into open position without shock. The check members 33 and 34 are provided with curved recesses which may be on the under side of the checks or extending laterally thereof. In the present instance the checks are provided with laterally extending sectors 35 having curved recesses 36 therein. Pivoted to doors 13 and 17 by suitable pivots 37 are bell cranks 38 and 39, one end of each of which carries a roller 40, 41 and the other end is adapted to slide in the recess 36 in the sectors 35. For cooperating with the free ends of the bell cranks 38, 39, I provide plates 42 and 43 having a wall attaching flange portion 42^a and 43^a and a horizontal portion 42^b and 43^b. In the portions 42^b and 43^b there are provided arcuate slots 44, 45, with which the rollers 40, 41, on bell cranks 38, 39, are adapted to cooperate when the doors are nearing closed position, the purpose of these plates 42, 43, being to draw the doors into tightly closed position by cooperation between the bell cranks and the slotted plates of the spring 95 checks 33 and 34. While I have shown the plates 42 and 43 as being separate members I may form them integrally with the check supports as shown in Fig. 8.

For locking the doors when in closed position I provide a pair of substantially longitudinally movable rods 46, 47, placed along the doorway 10 just above the opening therein. These rods are carried at their outer ends by brackets 48 and 49. The rods are also provided with L-shaped hook members 50, 51, mounted to engage projections 52, 52, mounted on doors 14 and 16, the projections in transverse section being preferably inclined towards the shaft 46. This may be clearly seen in Fig. 6. The inner ends of rods 46, 47, are pivotally connected to the lower portion 53 of a pivotally actuated mechanism. The actuating mechanism comprises lower portion 53 and upper portion 54 connected by pivot pin 55 (see Fig. 4). Lips 54^a and 53^a act to limit the movement of the parts 53 and 54. For holding the lips 53^a and 54^a, in contact there are provided rearwardly extending bosses 53^b and 53^c having a compression spring 53^d inserted therebetween, the operation of which will tend to keep the members 53 and 54 in substantial alignment. The member 54 is provided with an upwardly extending arm 56 carrying at its end a pin 57 adapted for cooperation with a spiral groove 58 in a collar 59 which is keyed to the shaft 25 as best seen in Figs. 1 and 4.

For operating the shaft 25 I employ an

electric motor 60 adapted to cooperate with a worm gear 61 mounted on sleeve 62 of the clutch member 27 (see Fig. 7). Splined on shaft 25 is a sliding collar 63 adapted 5 for cooperation with the sleeve 62 which collar is actuated by a bifurcated lever 64 pivoted to the doorway 10 at 65 and provided near its end with a spring 66 (see Fig. 1) adapted to hold the collar 63 in engagement with the collar 62, bifurcated arms 64^a cooperating with a depression 63^a in the collar 63.

The preferred manner of operating the doors comprises a reversing motor 60 operated by wiring such as that shown diagrammatically in Figure 12. When the motor is caused to operate in forward or reverse direction corresponding rotation of the shaft 25 results which rotates the vertical shafts 30 and 32 and the cams 67 carried at the lower ends thereof. These cams are carried within the check members 33 and 34 and each cam comprises an undercut or slotted portion 67^a and a truly circular surface or face 67^b shown in Figures 9 and 10. The checks 33 and 34 as shown comprise U shaped straps horizontally disposed with legs of unequal length. These straps 68 are mounted on the ends 20 of the shafts 30 and 32 with the shorter legs uppermost and the U embracing the cams 67. The outer ends of the longer legs are upturned and guide horizontally reciprocable plungers 69, which plungers are caused to bear against the cams 67 by coiled springs 70. For guiding the head end of the plungers the straps 68 are provided with upstanding pins 71 passing through slots 69^c in the plungers. The strength of the 30 spring 70 is such as to urge the plungers against the cams 67 at all times, the normal position of the parts being as shown in Figure 9 of the drawings. Under normal operation of the doors rotation of the motor rotates the shaft 25 and this in turn rotates the vertical shafts 30 and 32, rotating therewith the cams 67. By reason of the levers 38 pivoted to one of the doors of each set and having sliding cooperation 40 with the check members 33 and 34 in the slotted portion 36 thereof, the apparatus will function to swing the checks 33 and 34 with the cams 67 as the latter are rotated through connection with the shaft 25. The 50 springs 70 are of such strength as to maintain the plungers 69 against the inner faces 67^b of the cams 67. When the motor is caused to move the doors in either direction, by reason of mechanism in the motor circuit the motor is operated a sufficient length of time to move the doors throughout the paths of travel of the same. That is, from opened to closed position or vice versa. By reason of the limit switches the motor 60 is stopped when the doors have reached the

ends of their paths or when the motor has revolved a predetermined number of times. Whenever an obstruction is encountered by the doors in opening or closing full swinging of the checks 33 and 34 is impeded. Something has to give. In the types of devices now on the market that which gives is generally the motor which burns out. In my invention that which gives is the spring 70 in the checks 33 and 34. By reason of the positive connection between the cams 67 and the motor 60, rotation of the cams is continued as long as the motor operates which is until it reaches the predetermined number of revolutions 80 whereupon it is stopped by the limit switch. In view of the fact that the checks 33 and 34, or either of them, as the case may be, may no longer swing with the cam 67 by reason of an obstacle in the way of the door 85 the plunger 70 is pushed outwardly and is held against the truly circular face 67^b of the cam for such length of time as the truly circular face 67^b is in contact therewith. The cams 67 revolving at uniform speed 90 will therefore, as long as doors may be obstructed, reciprocate the plunger 70 until the motor is stopped. It will be apparent therefore, that by my invention it is possible to provide a motor for continuous operation in one direction to open the doors and in a reverse direction to close the same and which motor may be controlled to revolve a predetermined number of times in each direction and brought to a stop. 95 By my invention it is possible to permit the obstruction of the doors connected with the motor at any point in the travel thereof without in any manner hindering the operation of the motor or causing damage of 100 any sort to the motor or to the mechanism connecting it with the doors.

By provision of safety stop switches, to be explained hereinafter, the motor may be stopped at any time irrespective of the position of the doors. Suppose, for instance, the motor were arranged to run only so long as to move the doors from closed to opened position vice versa and one of the doors strike an obstruction. When the motor has run a sufficient length of time as stated, the stop switch is actuated thus stopping the motor in which condition the cam 67 would be in a position opposite to that shown in Fig. 8, that is, would be turned through an angle approximating 180°. The door being in the position shown in Fig. 10, the inner face 69^c of the plunger would be against the truly circular face 67^b of the cam and nothing would happen to the door 110 or to the operating mechanism as the spring could not act to move the plunger. The elements being in this position if the door is moved so that the inner face of the member 69^c of the plunger passes over the end 115

surface 67^c of the cam 67, the spring immediately will act to force the plunger into the slot 67 which will cause the bracket 68 and the door attached thereto to move into position of rest for the spring, that is, when the plunger is in full engagement with the arcuate member of the cam, which action will move the door into fully opened position without the aid of mechanical or manual means.

It is understood that the doors being in opened position the closing would operate in the reverse manner and if the doors were stopped in closing, the cam would operate as described above in the reverse direction. If it should happen that the motor be operated with the doors in either fully opened or fully closed position and if the limit switches did not operate to stop the motor, then the continued operation would cause the cam 67 to rotate, which rotation would reciprocate the plunger without opening or closing the doors or causing any damage of any nature to any of the parts.

It is sometimes necessary to provide means for manually opening or closing doors operated by mechanical means. In the present instance, I have provided chains or ropes 76 and 77 as seen in Fig. 1, the end 30 of 76 being connected to the lower end of arm 64 which operates the sliding collar 63 in the clutch 27 and the rope 77 being connected to the lower portion of the member 53 of the tripping mechanism. If it is desired to open the doors manually the rope 76 is pulled thereby disengaging the clutch 27 permitting the shaft 25 to be freely revoluble and the rope 77 is operated to actuate the locking mechanism to unlock the door and the door may be opened in the usual manner.

Referring to Fig. 12, I shall explain the preferred form of wiring which is employed. It must be understood that the motor control is no part of my invention as any controlling apparatus for electric motors which will cause the motor to run in one direction for a certain length of time and be manipulated to operate in a reverse direction and be automatically stopped would be sufficient for operating the motor used in connection with my door operating mechanism. The connections to the line are indicated by A and B, A representing the line conducting the current into the various switches, etc., and B the return circuit. C and D are magnetic cut-out switches of any well known type, the contact members being normally out of engagement and adapted to be thrown into engagement by the energizing of either one of the magnets or solenoids used in connection with these magnetic switches. The solenoids are indicated by E and F. It is understood that one of these solenoids is so connected as to operate the switch which

will cause the motor to open the doors and the other to cause the motor to operate in the reverse direction for closing the doors. The motor is indicated by G. For energizing solenoid F to close the switch D, a contact 80 is employed which is adapted for making a momentary contact only. Connected in the circuit which is made when the contact 80 is closed is a limit switch 81 which is adapted to be actuated by the door on reaching the fully opened position which engagement will break the circuit through the switch 81, thus cutting off the energizing current through the solenoid F and permitting the switch D to open, thus stopping the motor. To provide a positive means of stopping the operation of the motor at any time irrespective of the position of the doors I prefer to pass the negative lead from both solenoids E and F through switches 82 and 83 which are normally closed and which are connected at 84 with the negative main line lead B. 85 is a lead from main A to the contacts 80, 86, 87 and 88 all of which operate in the same manner. Contacts 80 and 86 may be placed at any convenient point for actuating the motor and points 87 and 88 may be placed at some other point, even at a remote point if desired so that actuation of contacts 80 and 88 will cause the doors to open and 86 or 87 to close.

89 is a limit switch similar to 81 adapted to be actuated by the doors when moved into closed position. To prevent either switch C or D from being closed while one is in closed position, I employ a bell crank 90 so pivoted as to be moved by the arms of the switches D and E when either set of arms is moved into closed or contacting position. This will cause the other end of the bell crank 90 to move outwardly and if the switch which is opened is attempted to be closed the bell crank will throw out the switch which is closed thus preventing any burning out of the motor or damage to the train of mechanism.

For moving the doors to open position when they are closed a momentary contact is made by the switch 80 which closes the circuit indicated by the letter a, that is the current enters through the main A and nears the course through the contact 80, limit switch 81 energizes the solenoid F which causes switch D to close making contact between points 92 and 93 and connection at 94 with the motor G. When the contact 80 is broken solenoid F is energized by means of the shunt which follows the course indicated by the letter b that is, comes from the main A through the points 92 and 93 and then through limit switch 81 around the solenoid F back through stop switches 82 and 83 to the negative lead B at 84. It will be seen that this shunt circuit will energize the lead F so long as switches 81, 82 and 83

130

remain closed. As soon as any one of these is opened, switch 81 by the doors or 82 or 83 by a person, the energizing current to the solenoid will be broken, hence the switch D 5 will open and stop the motor. To close the doors contact 86 or 87 may be actuated in which case the circuit may be made by closing either contact 86 or 87 as indicated by the numerals *c* and follows the same course 10 as followed in the first instance, namely, through the contact 86, limit switch 89, solenoid E, stop switches 82 and 83 to the negative lead B at 84. The energizing of the solenoid E will close the switch C. When 15 the contact 86 or 87 is broken a shunt circuit is formed as described for keeping the switch C in contact and is broken by the limit switch 89 over the stop switches 82 or 83. It will be seen that with this wiring 20 control, it is possible to position one button station comprising the momentary contacts 80 and 86 and the limit switches 82 at any place and at some other place either outside or inside of the building momentary contacts 25 87 and 88 and the stop switch 83 so that the doors may be opened by any one within the building or if one of the button stations is positioned on a post outside of the building may be opened or closed by making the 30 proper contacts. The limit switches 81 and 89 are positioned on the doorway or wall of a building in any convenient place to be actuated by the doors.

In Figure 13 I have shown one means 35 for preventing the two magnets E and F from being energized at the same time. This means includes armatures K and an angle arm 90 pivoted by means of a pin 90^b to a bracket 90^a suitably secured adjacent the coils E and F. The ends of the arm 90 contact the armatures K, so that when the armature of the magnet E is energized as shown in the drawings, the armature of the magnet F cannot be attracted 40 to the magnet without moving the armature K of the magnet E out of contact therewith, thus preventing any liability of the 45 two circuits being closed at the same time.

The operation of the device is as follows: 50 The doors being in closed position as shown in Figs. 1 and 2 the motor 60 is caused to operate by closing of either one of the momentary contacts 80 or 88 which will energize the solenoid F, close the switch D and cause the motor to operate in a direction to move the doors from closed to opened position. The moment the shaft 25 starts to rotate the trip mechanism 59 is actuated as the pin 57 is moved forward 55 in the spiral groove 58 moving the rods 46 and 47 away from engagement with the stops 52, 52. The rotation of the shaft 25 causes the vertical shafts 30 and 32 to rotate which moves the checks 33 and 34 outwardly tending to act upon the door through

the pivots 37. Because of the checks 33 and 34 the power is applied to the doors gradually and not suddenly as would be the case if the checks were not interposed in the power transmitting train, the application 70 of the power being through the springs 70. Continued operation causes the doors to be opened and moved into the position shown in Fig. 3 and into engagement with the limit switch 82 opening the latter and thus 75 stopping the motor. The stoppage of the motor is sudden hence, the stoppage of rotation of the shaft 25 and its allied connections is likewise sudden. This would result in immediate and sudden stoppage of 80 the doors which might result in injury to some of the operating parts. However, the checks 33 and 34 absorb the shock which would be imposed by the doors by the sudden stoppage of the operating train and permit them to approach opened position gradually.

When it is desired to close the doors the proper switch connections are made as described above. Similarly with the beginning 90 of the opening operation the doors are moved from opened position gradually and towards closed position. It is apparent that if the doors were slammed into closed position, some of the parts might be damaged 95 so as to prevent further opening of the doors or proper operation by the motor 60. Furthermore, a tight closing of the doors might not result. To act as a check in closing the doors, also as a means for assuring 100 their being tightly closed the slotted plates 42, 43 are provided and also the bell cranks 38, 39. The rollers 40, 41 on the free ends of the bell cranks 38, 39 enter the slots 44, 45 and bear thereagainst. This engagement 105 operates against the springs in the checks 33, 34 which checking is transmitted to the doors through the pivotal connection between the checks on the doors, thereby retarding the movement of the doors and 110 bringing them into closed position gently and also assuring their being moved into closed position because of the cooperation 115 between checks 33, 34 and the bell cranks 38, 39 in engagement with the plates 42, 43, and the action of the springs 70. As the doors move into tightly closed position the motor control 67 will stop the motor 60.

Often times it happens that when the doors are being closed an obstruction such 120 as a block or perhaps a vehicle may be in in the doorway. With the ordinary means of operating such doors when an obstacle is encountered the mechanism continues to operate and there results breakage of some 125 portion of the operating mechanism or of the door or perhaps damage to the obstacle. It is an important part of my invention to provide for the operation of the closing mechanism of my device when any of the 130

doors encounter obstacles and also to provide means for closing the doors after the obstacle has been removed and after the electric motor has been stopped. Also, 5 there has been no damage done to the operating train. The absence of damage to the operating train is due to the interposition of the checks 33, 34 as the power application from the shaft 25 has been transmitted to the checks where the power has been absorbed and has not been transmitted directly to the doors as is the case in the present method of operation.

The compression of the springs 70 causes 15 power to be stored therein so that when the obstacle against the doors is removed, the doors will be closed by operation of the spring compressed plunger against the arcuate faces 67^b of the cam 67 as hereinabove 20 described.

I do not limit my invention to the exact form shown and described as I am aware that modifications of such devices are possible and that such modifications I consider 25 as coming within the scope of my invention.

Having fully described my invention, what I desire covered by Letters Patent is:

1. In a device for operating folding doors, 30 the combination with a doorway, of hinged folding doors mounted therein, a track across the top of said doorway, hangers on said doors cooperating with said track, an electric motor for opening and closing said 35 doors, and other means operated by said motor for locking said doors when in closed position.

2. In a device for operating folding doors, 40 the combination with a doorway of hinged folding doors mounted therein, a track across the top of said doorway, hangers on said doors cooperating with said track, means including an electric motor for opening and closing said doors, and positively 45 actuated separate means operated by said closing means for locking said doors in closed position.

3. In a mechanism for operating folding doors, the combination with a doorway, of 50 hinged folding doors mounted therein, tracks mounted along the top of said doorway, hangers on said doors for engaging said tracks, means for operating said doors, means cooperating with said operating 55 means for locking said doors in closed position, and means included in said operating means to move the doors into tightly closed position.

4. In a mechanism for operating folding 60 doors, the combination with a doorway, of hinged folding doors mounted therein, tracks mounted along the top of said doorway, hangers on said doors for engaging said tracks, means including an electric 65 motor for operating said doors, means for

moving the doors into tightly closed position, means cooperating with said operating means for locking said doors when in tightly closed position, and means operable by the doors for automatically stopping said operating means after a predetermined operation thereof.

5. In a mechanism of the class described, 70 the combination with a doorway, of hinged folding doors mounted therein, tracks mounted on the lintel of said doorway and maintained at an angle thereto, brackets for supporting said track, hangers on the doors adapted for engagement with said tracks, and power actuated means for opening and closing and locking the doors in closed position, the locking means including a member 75 separately actuated by said motor.

6. In a mechanism of the class described, 80 the combination with a doorway, of hinged folding doors mounted therein, tracks mounted on the lintel of said doorway and maintained at an angle thereto, brackets for supporting said track, hangers on the doors adapted for engagement with said track, and power actuated means for opening and closing the doors including means for moving the doors into tightly closed position.

7. In a mechanism of the class described, 85 the combination with a doorway of hinged folding doors mounted therein, tracks mounted on the lintel of said doorway and preferably maintained at an angle thereto, brackets for supporting said track, hangers on the doors adapted for engagement with said tracks, means for moving the doors into opened or closed position, including supplemental means for moving the doors into tightly closed position and means for locking the doors in closed position.

8. In a mechanism for opening and closing folding doors including a doorway, hinged folding doors hung therein, means mounted on the lintel of said doorway for opening and closing said doors, other means operable by said opening and closing mechanism to lock the doors in closed position, and yielding means including a spring check interposed between the opening and closing mechanism and the doors.

9. In a mechanism for opening and closing folding doors comprising a doorway, hinged folding doors hung therein, means mounted adjacent said doorway for opening and closing said doors, means operable by said opening and closing means to lock the doors in closed position, yielding means including a spring check interposed in said closing means, and arms connecting the 115 yielding means and the doors.

10. In a door opening and closing mechanism, the combination of a doorway, hinged folding doors mounted therein, a shaft on the lintel of said doorway, a motor 120

adapted for the rotation of said shaft, independent means operable by said shaft for locking the doors when in closed position, a clutch in said shaft, manually operable means for actuating said clutch, and manually operable means for actuating said independent means whereby said doors may be manually operated.

11. In an opening and closing mechanism for folding doors, the combination of a doorway, hinged folding doors hung therein, a shaft rotatably mounted on the lintel of said doorway, means for rotating said shaft, and locking means on said lintel operable by said shaft for locking the doors in closed position.

12. In a door opening and closing mechanism, the combination of a doorway, of hinged folding doors mounted therein, a shaft rotatably mounted on the lintel of said doorway, means for rotating said shaft, a clutch on said shaft for disconnecting said rotating means, mechanism operated by said doors adapted to stop said rotating means, locking bars mounted on the doorway provided with a tripping mechanism, said tripping mechanism adapted to be actuated by said shaft, hooks on said locking bars, wedges on the doors adapted for cooperation with said hooks, tracks mounted on the lintel of the doorway, connections between said shafts and said doors including shock absorbing means, said connections pivotally connected to said doors, whereby said doors may be moved.

13. In a device for operating folding doors, comprising in combination means for slidably supporting the doors, power actuated means for opening and closing the doors, and means connecting said power actuated means and the doors for closing them independently of said power actuated means, said means including an arm attached to the door intermediate its ends.

14. In a device for operating folding doors, comprising in combination means for slidably supporting the doors, power actuated means for opening and closing the doors, said means including a spring check, means connecting said power actuated means with the doors for closing the doors independently of said opening and closing means, and means operable by the opening and closing means for locking the doors in closed position.

15. In a device for operating folding doors, the combination of means for slidably supporting the doors, power actuated means including shock absorbing means for opening and closing the doors, and means connected with the shock absorbing means for moving the doors into tightly closed position.

16. In a device for operating folding doors, the combination of means for slid-

ably supporting doors, power actuated means including shock absorbing means for opening and closing the doors, and means cooperating with the shock absorbing means to move the doors into tightly closed position.

17. In a device for operating folding doors, the combination of means for slidably supporting doors, power actuated means including shock absorbing means for opening and closing the doors, means connecting the power actuating means with the doors for closing the doors independently of the operating means, and means including a lever cooperating therewith to move the doors into tightly closed position.

18. In a mechanism for opening and closing folding doors, the combination of a doorway, hinged folding doors mounted therein, tracks adjustably supported on the lintel of the doorway and maintained at an angle thereto, hangers on the doors adapted for cooperation with the tracks, a shaft rotatably mounted on the lintel, means for rotating said shaft, a clutch on said shaft whereby the shaft may be disconnected from rotation by said rotating means, gears on the ends of the shaft, vertically disposed shafts adapted for engagement with the gears on said shaft, spring checks mounted on the vertical shafts and adapted for movement therewith, bell cranks pivotally mounted on the doors and having sliding pivotal connection with said checks, friction reducing means secured to the free ends of said cranks, brackets secured to said lintel and provided with arcuate slots, with which the free ends of said bell cranks are adapted to engage whereby to move the doors into tightly closed position, means operable by said shaft for locking the doors in closed position, wedges on said doors adapted for cooperation with said locking means, a reversing means operable by said shaft rotating means, manually operable means for disconnecting the shaft rotating means from the shaft, and manually operable means for actuating said locking means whereby the doors may be freely moved.

19. In a mechanism for opening and closing folding doors, the combination of a doorway, hinged folding doors mounted therein, tracks adjustably supported on the lintel of the doorway and maintained at an angle thereto, hangers on the doors adapted for cooperation with the tracks, a shaft rotatably mounted on the lintel, means for rotating said shaft, vertically disposed shafts adapted for engagement with said shaft, yielding means cooperating with the vertical shafts and adapted for movement thereby, levers on said doors and connected with the said yielding means, brackets secured to the lintel of said doorway and provided with slots with which the free end of said levers

- are adapted to engage whereby to move the doors into tightly closed position, means operable by said shaft for locking the doors in closed position, manually operable means 5 for disconnecting the shaft rotating means from the shaft, and manually operable means for actuating said locking means whereby the doors may be freely moved.
20. In a device of the class described, the 10 combination of a shaft, power means for actuating said shaft, yielding means adjacent said shaft and having operative engagement therewith, a lever movably connected to said yielding means and adapted for connection with a door at a point intermediate its ends, and a friction block mounted for engagement by the free end of said lever whereby to oppose movement of said lever by said yielding means.
20. 21. In a device of the class described, the 15 combination of a shaft, power means for actuating said shaft, yielding means mounted adjacent the shaft and having operative connection therewith, a lever having slidable connection at one end with said yielding means and adapted to be pivoted intermediate its ends to a door, a friction plate adapted for engagement by the free end of said lever whereby movement of the 25 door is checked.
22. In a device of the class described, the 20 combination of a shaft, power means for actuating said shaft, yielding means mounted adjacent the shaft and having operative connection therewith, and an arm 25 connecting said yielding means and door, said arm having pivotal engagement with the door and sliding engagement with the yielding means whereby motion imparted 30 to said yielding means by said shaft is imparted gradually to said door thereby moving same, whereby continued operation of said shaft is unaffected when said door is obstructed.
45. 23. In a locking device for folding doors, the 25 combination of a shaft, power means for actuating said shaft, a cam on said shaft, a reciprocable bar mounted in substantially parallel relation to said shaft, a tripping 30 mechanism connected to said bar and operable by said cam to reciprocate said bar when said shaft is rotated, and means on said door adapted for engagement by said reciprocable bar.
55. 24. In a device for locking folding doors, the 30 combination of a shaft, power means for actuating said shaft, a cam on said shaft, bars mounted in substantially parallel relation to said shaft and adapted for 35 reciprocation, a rocker having operative engagement with said cam and secured to said
- bars whereby the bars are reciprocated when said shaft is rotated, and means on said doors for cooperation with said bars when the latter are actuated. 65
25. In a device of the class described, the 40 combination of folding doors, power actuating means therefore, means operable by said power means for locking the doors in closed position, and manually operable means for disconnecting said locking means from said power means whereby the doors may be manually opened, and means on said doors for cooperation with said bars when the latter are actuated. 70
26. In a device of the class described, the 45 combination of a shaft, power means for actuating said shaft, a cam on said shaft, bars mounted in substantially parallel relation to said shaft and adapted for reciprocation in opposite directions, a rocker having operative engagement with said cam and secured to said bars whereby the bars are reciprocated when said shaft is rotated, and means on said doors for cooperation with said bars when the latter are actuated. 75
27. In a door operating mechanism, the 50 combination with sliding doors, of power means adapted for moving the doors into fully closed or opened position, and a member including a reciprocating plunger and a spring connecting said power means and said doors adapted for the conservation and dissipation of energy created by said power means when actuated whereby said doors are moved from a partially opened or closed position to fully opened or closed position whenever said power means are stopped before said doors are completely opened or closed thereby. 80
28. In a door operating mechanism, the 55 combination with sliding doors, of power means adapted for moving the doors into fully closed or opened position, a member including a reciprocating plunger and a spring connecting said power means and said doors adapted for the conservation and dissipation of energy created by said power means when actuated whereby said doors are moved from a partially opened or closed position to fully opened or closed position whenever said power means are stopped before said doors are completely opened or closed thereby and means for cooperating with said member for moving the doors into 85
- fully closed position. 90
